ORNAMENT FOR AN AUTOMOBILE OR THE LIKE

Fedele Bianco, Grosse Pointe Woods, Mich., assignor to
General Motors Corporation, Detroit, Mich., a corpora-
tion of Delaware

Application July 25, 1957, Serial No. 47,086

Term of patent 7 years

(Cl. D14—6)

Figure 1 is a front elevational view of an ornament for an automobile or the like according to my new design;

Figure 2 is a top plan view of the ornament;

Figure 3 is an enlarged elevational view of the ornament;

Figure 4 is an enlarged sectional view taken on the plane indicated by line 4—4 of Figure 1;

Figure 5 is an enlarged sectional view taken on the plane indicated by line 5—5 of Figure 1;

Figure 6 is an enlarged sectional view taken on the plane indicated by line 6—6 of Figure 1; and

Figure 7 is an enlarged sectional view taken on the plane indicated by line 7—7 of Figure 1.

I claim:

The ornamental design for an ornament for an automobile or the like, substantially as shown.

UNITED STATES PATENT OFFICE
CERTIFICATE OF CORRECTION

Design No. 182,988

June 10, 1958

Fedele Bianco

It is hereby certified that error appears in the printed specification of the above numbered patent requiring correction and that the said Letters Patent should read as corrected below.

Column 1, line 4, for "Figure 3 is an enlarged elevational view" read
-- Figure 3 is an enlarged side elevational view --.

Signed and sealed this 12th day of August 1958.
